DESIGN FOR A BADGE OR SIMILAR ARTICLE

Aldon N. D. Attayer, Highland Park, Pa.

Application March 5, 1942, Serial No. 106,093

Term of patent 14 years

To all whom it may concern:

Be it known that I, Aldon N. D. Attayer, a citizen of the United States, residing at Highland Park, county of Delaware, State of Pennsylvania, have invented a new, original, and ornamental Design for a Badge or Similar Article, of which the following is a specification, reference being had to the accompanying drawing, forming a part thereof.

In the drawing:

Fig. 1 is a plan view of a badge or similar article showing my new design.

Fig. 2 is a side elevation thereof.

The dominant features of my design are shown in full lines in the drawing.

I claim:

The ornamental design for a badge or similar article, substantially as shown and described.

ALDON N. D. ATTAYER.
